UNITED STATES PATENT OFFICE.

GEORGE C. WEISS, OF SAN FRANCISCO, CALIFORNIA.

BED-SPRING.

1,289,061.

Specification of Letters Patent. Patented Dec. 24, 1918.

Application filed May 16, 1917. Serial No. 169,034.

To all whom it may concern:

Be it known that I, GEORGE C. WEISS, a citizen of the United States, residing at San Francisco, in the county of San Francisco and State of California, have invented certain new and useful Improvements in Bed-Springs, of which the following is a specification.

This invention relates to bed springs, and the primary object is to provide an improved construction for bed springs, whereby an added resiliency may be obtained for supporting a mattress or the like, so that ease and comfort may be provided for the person using the device.

The invention also aims to provide a device of this character that will include a plurality of supporting wires of a length substantially equal to the length of the bed spring and resiliently supported, whereby an even resilient support may be provided for the mattress.

A further object of this invention is the provision of a bed spring which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, wherein is illustrated the preferred form of my invention, in which;

Figure 1 is a side elevation.

Fig. 2 is a top plan.

Fig. 3 is an end elevation.

Fig. 4 is a detail section on the line 4—4 of Fig. 2.

Referring to the drawing, wherein is illustrated the preferred form of my invention, and in which like numerals of reference indicate corresponding parts throughout the several views, the frame includes the side rails 1 and 2 each of which comprises pivoted rail sections 3 and 4. These rail sections are preferably constructed from lengths of pipe having portions of their length flattened to provide the engaging faces 5, adapted to be held in contact by the pivot bolts 6 which serve as pivots for the rail sections in each rail. In this connection,

it is pointed out, that the rail sections may be constructed from lengths of wood or other suitable material having portions cut away to provide the said flat surfaces 5.

The terminals of the upwardly extending ends of the rail sections are provided with sleeves 7 to which are integrally connected the lugs 8. This provides two lugs at each end of the device, and the same are provided with openings for receiving the end rail 9, the terminals of which are flush with the outer sides of the corresponding lugs. An elongated clamp is fastened to each end rail 9 and each clamp consists of a plate bent into substantially cylindrical form to fit the rail 9 and having its marginal edges brought together to provide an inwardly projecting flange 10, provided with longitudinally spaced apertures for the reception of the ends of the coil tension springs 11. These springs, as clearly shown by Fig. 2 of the drawing, project inwardly of the frame and their proximate ends are connected together by the heavy wire strands 12 which form the resilient support for the mattress or the like.

The downwardly extending ends of the rail sections have their terminals provided with openings through which supporting rods 13 are projected and the ends of these rods are extended beyond the sides of the rails, so that they may engage the frame of the bed to support the device in position. Projecting inwardly from each sleeve 7 is a lug 14 to which one end of a tension spring 15 is connected, the opposite end being fixed to a convenient lug carried by the rod 13 as shown by Fig. 3 of the drawing. These springs 15 tend to draw the rail ends together, and assist the springs 11 in tensioning the strands 12, so that the strands will be drawn taut to support the mattress. It will be apparent that the pivotal connection of the rail sections will permit relative movement of the latter, so that the height of the strands 12 with respect to the bed frame may be altered as desired.

From the foregoing it will be observed that a very simple and durable bed spring has been provided, the details of which embody the preferred form. I desire it to be understood, however, that slight changes in the minor details of construction may be

made without departing from the spirit of the invention or the scope of the claim hereunto appended.

I claim:

- 5 A bed spring comprising side rails; each including pivoted rail sections having their ends movable toward and away from each other and extended upwardly and downwardly, sleeves fixed to the upwardly extending ends of the rail sections, end rails carried by the said sleeves, a supporting
- 10

rod at each end of the downwardly extending ends of the rail sections, resilient supporting means connected to the said end rails, and tensioning elements fixed to the 15 said sleeves and the said supporting rods.

In testimony whereof I affix my signature in presence of two witnesses.

GEORGE C. WEISS.

Witnesses:

E. T. VON BUELOW,
WALTER MILLER.
